UNITED STATES PATENT OFFICE.

J GROVE BROWN, OF GROTON, NEW YORK.

STONE-SPREADING MACHINE.

1,220,945.

Specification of Letters Patent. Patented Mar. 27, 1917.

Application filed October 21, 1913. Serial No. 796,436.

To all whom it may concern:

Be it known that I, J GROVE BROWN, a citizen of the United States, residing at Groton, in the county of Tompkins and State of New York, have invented certain new and useful Improvements in Stone-Spreading Machines, of which the following is a specification.

The purpose of this invention is to provide mechanism for dumping stone or like road material upon roadways, and for simultaneously spreading the same in layers of even depths.

In building roadways with broken or crushed stone foundations, it is customary to first smooth off the surface of the dirt roadway, giving it the proper crown or arch, and to throw up ridges or shoulders at the sides for retaining the crushed stone. The crushed stone is usually dumped on or near the roadway and spread out as evenly as possible by manual labor. It is of importance to have the material spread to an even depth and also to have the fine and coarse material evenly distributed; otherwise, when the layer of stone is rolled it will become more compact in some places than in others. When the material is dumped on the roadway and spread by forks and rakes, in the customary way, the coarser material is spread and the finer material mostly remains where the load was dumped, resulting in uneven compacting of the layer when rolled. Some road engineers require that the material be dumped on dumping boards, from which it is spread by means of shovels so as not to destroy the evenness of the mixture. This process is expensive, and even with the greatest care in spreading, the layer of stone will be of uneven depth in different places, and, when rolled, will be unevenly compacted.

In carrying out my invention, I provide, in connection with a dumping vehicle for transporting and dumping the stone, an arrangement of chutes and auxiliary devices for automatically laying the stone in layers of various widths and even depths upon the roadway as the load is dumped. The arrangement is such that the layers or courses may be laid at one or both sides of the planes of the vehicle wheels, (as well as between the planes of the wheels) so that in dumping successive loads, side by side, the vehicle wheels need not travel upon the previously laid stone. The evenness of the

mixture as delivered into the vehicle is also maintained in its delivery upon the roadbed, and the apparatus is automatically adjustable for vehicles having spring supported bodies, so that changes in the height of the body with respect to the roadway, owing to light or heavy loading, or to release of the load, will not affect the depth of the layer of stone being laid.

In the accompanying drawing, forming part of this specification, and which illustrates my invention,

Figure 1 is a side elevation of a dumping vehicle, equipped with my improvements, showing the parts in position to dump and spread material upon a roadway;

Fig. 2 is a rear elevation of the chutes in dumping positions;

Fig. 2^a is a top plan view of one of the trailing gage members;

Fig. 3 is a vertical section on the line 3—3 of Fig. 2;

Fig. 4 is a section through the chutes on the line 4—4 of Fig. 1, the delivery end of only one chute being shown;

Fig. 5 is a vertical section through the delivery end of one of the chutes, illustrating the adjustment;

Fig. 6 is a section on the line 6—6 of Fig. 5;

Fig. 7 is a front elevation of the vehicle body showing the bracket to which the hoisting cable is attached, and the guide cams for centering the body on the frame when the body is lowered; and,

Fig. 8 is a side elevation of the hoisting and lowering mechanism for dumping the vehicle.

Referring to the drawings, A indicates an endwise dumping vehicle comprising a frame α , forward wheels α' , rear wheels α'' , and a body α^3 . The body is journaled upon a shaft 1 which is mounted in brackets 2, secured to the frame near the axles of the rear wheels, and is adapted to be tilted rearwardly by means of suitable hoisting and lowering mechanism B, hereinafter referred to. Secured to the rear end of the body is a main chute C, which diverges laterally, as shown in Figs. 2 and 4, the lower end of the chute extending some distance beyond the planes of the vehicle wheels. This main chute is subdivided by partitions 3, 4, and 5, into a plurality of smaller chutes 6, 7, 8, and 9. Connected to the lower ends of the several chutes are hinged extensions 6^a, 7^a,

8^a, and 9^a, which form the delivery ends of the chutes. The several delivery portions of the chutes are alike in construction, and, as shown in Figs. 3 to 6, inclusive, each delivery end comprises two telescopic sections 10 and 11, the former fitting over the mouth of the fixed chute, to which it is hinged at its sides by studs 12, located near the front faces of both members, as shown. This permits the delivery end of each chute to swing vertically to a limited extent. The outer section 11 is provided with perforations 11^a, and by means of bolts 13 adapted to fit said openings, one section may be adjusted upon the other to vary the length of the chute. Filling pieces 14 are arranged between the sections in order that one section may slide easily within the other, to allow adjustment, and to prevent the parts from rattling when the vehicle is in motion.

As hereinafter explained, when the parts are in position to deliver material upon the roadway, the lower edge 11^b of the section 11 is substantially parallel with the roadway. The rear side of the section 11 has its lower portion 11^c substantially at right angles to the end 11^b, and secured to the part 11^c is a scraper 15, which is adjustable vertically by means of bolts 16 fitting within slots 15^a in the scraper. This scraper normally extends below the mouth of the chute, as shown in the several figures of the drawing.

A gate 17 is provided for closing the entrances to all of the chutes in the casing C, and gates 18 are provided for closing the entrances to the individual chutes. The back of the casing C is cut away, as shown at c, between the angle irons 19, and mounted in said angle irons is a shaft 20, provided with devices, projecting through the opening in the casing, for operating the main gate 17. These devices consist of levers 21, secured to the shaft and hinged at their free ends to links 22 which are pivotally connected at 23 to the back of the gate 17. The links 22 are U-shaped in cross section and the levers 21 are pivoted between the sides of the links. The arrangement is such that when the shaft is turned in one direction, the gate will be closed, as shown in full lines in Fig. 3, the arm 21 and link 22 forming a toggle which locks the gate in its closed position, and when the shaft is turned in the opposite direction, the toggle will be broken and the gate will be swung to its open position, shown in dotted lines in Fig. 3, wherein the gate closes the opening c in the back of the casing C. The shaft 20 is rocked by means of a crank 20^a, secured thereon and a hand rod 20^b extending along the side of the vehicle body to the front end thereof. When the vehicle is tilted and the main gate 17 opened, as described, the material flowing from the body of the vehicle

into the casing will hold the gate in its open position. The material will flow through such of the chutes as are not closed by their gates 18. If it is desired to permit the material to flow through any particular chute, the gate 18 of that chute is opened before the gate 17 is opened to admit the material to the casing C. As shown in Fig. 3, each gate 18 is provided with a finger hole 18^a, too small to let the broken stone pass through, but large enough to permit the operator, by inserting his arm through the opening c, to insert his fingers through opening 18^a and swing the gate into the dotted position, thus opening the chute. When the gates 18 are in their open positions, they are held by suitable latches 18^b on the casing C, which engage openings 18^c in the gates. Thus the gates of all or any of the individual chutes may be opened as desired and the main gate may then be opened and the material will flow through only such of the chutes as are not closed by their gates.

When the vehicle body is in the tilted position, the delivery end portions 6^a, 7^a, etc., of the chutes are supported upon trailing gage members D, D', and D'', one of which is shown in plan view in Fig. 2^a, these members holding the delivery ends of the chutes and the scraper bars thereon at predetermined distances from the ground. As shown, each gage member comprises a fork 24 which is journaled upon a shaft or rod 25 secured in the brackets 2, and between the arms of the fork is mounted a gage wheel 26 adapted to roll upon the ground when the vehicle body is tilted. Connected to the arms of the fork and extending rearwardly from the gage wheel are rails 27, spaced apart from one another by suitable spacers 28, these rails, when the gage wheel engages the ground being substantially parallel with the road surface. In order to support the movable ends of the chutes upon the gage members, the sections 11 of the chutes are provided with brackets 29 in which are journaled grooved rollers 30, which rest upon the rails 27. These brackets, and the rollers thereon, are held in fixed relation to the inner sections 10 of the delivery ends of the chutes by the bolts 13, so that these sections remain at substantially the same height from the ground at all times when the wheels of the gage members are on the ground. The holes 11^a in the outer chute sections 11 are evenly spaced apart, the distance between the holes in each section being such that the distance of its outlet end from the ground may be adjusted one inch by changing the bolts from one pair of holes to an adjacent pair. Thus, the sections 11 can be adjusted to spread the material two, three, four, five, or six inches thick, and, for fractions of an inch, the scrapers can be ad-

justed on the sections 11. To keep the rollers against the rails at all times, and particularly to avoid chattering when the apparatus is traveling on the road, the delivery ends of the chutes are firmly pressed downward by springs 31 which are arranged between brackets 32 on the delivery ends of the chutes and brackets 33 on the casing C. For lifting the gage members clear of the ground 10 when the vehicle body is returned to its normal position, chains 34 are provided, which connect the yokes 24 with the body of the vehicle at the rear of the rear axle. It will be evident that when the body is brought to 15 its normal position, the gage members will be lifted and the movable portions of the chute will remain supported thereon, and whenever the vehicle is tilted into the dumping position the gage members will engage 20 the ground and the scrapers will be held at a distance from the ground which is determined by the adjustment of the chute sections 11 on the sections 10, and the adjustment of the scrapers on the sections 11. It 25 is desirable to have the gage wheels close to the outlet ends of the chutes in order that the latter may not be moved up and downward by the rocking of the yoke and rails to any considerable extent when the vehicle 30 wheels are traveling over uneven ground.

It is presumed, of course, that before laying the stone on a dirt roadway, the latter will be smooth. An important feature of my invention is the arrangement of the supporting rollers 30 close to and practically in the plane of the scrapers. Thus, any slight rocking of the chute will not cause any appreciable change in the height of the scraper, due to its rocking motion about its 40 point of support. As a certain amount of space is required between the delivery ends of adjacent chutes to accommodate the gage rails, the adjacent scrapers are provided with extensions 15^b, for closing the gaps between them so that the material will be spread evenly at all points.

For tilting the vehicle and returning it to its seat, a windlass 35 is supported at the front of the vehicle upon an upright 36, and 50 a chain or cable 37 is wrapped around the windlass and has its ends connected to eyes 38 and 39, the former attached to the front end board 40 of the vehicle, and the latter attached to the lower end of a fork 41, which 55 is secured to said front end. The fork is provided with a cross-piece 42 having downwardly projecting cams 43 thereon, which engage the sides of the frame *a* as the vehicle body is lowered, these cams serving to center the body upon the frame. A spring 60 actuated locking bolt 44, suitably mounted in the upright 36 and an angle iron 45, the latter attached to one side of the frame *a*, is adapted to extend over the upper end of 65 one of the cams 43, when the vehicle body is

lowered, and thereby lock the body against tilting. This bolt may be actuated to release the body by means of a foot lever 46, connected by a rod 47 to a bell crank 48 which is attached to the bolt.

The operation of the vehicle, in laying stone upon a roadway is as follows:

If it is desired to deliver upon the roadway a layer of stone of the entire width of the several chutes, after the body has been tilted, all of the gates 18 are moved to their open positions and the main gate 17 is then opened. The parts having been adjusted so that the distance between the lower edges of the scraper bars and the ground is equal to 70 the depth of the layer of stone which it is desired to place upon the roadway, the vehicle is pulled forward, and the stone passing through the chutes is laid upon the ground as the vehicle moves, the scrapers leveling 75 off the stone to the desired depth. As the trailing gage members are movable vertically, independently of one another, if the road is crowned the gage member or members traveling over the higher portions of 80 the ground will raise the chute or chutes which it supports relatively to the other chute or chutes, so as to maintain a substantially even depth of stone on the various portions of the road. In the drawing, (Fig. 2) 85 the delivery ends 7^a and 8^a of the central pair of chutes are supported at both sides, the end 7^a being supported by the gage members D and D', and the end 8^a being supported by the gage members D' and D², while 90 the delivery ends 6^a and 9^a of the side chutes are each supported by only one gage member, the end 6^a being supported by the member D, and the end 9^a being supported by the member D². In moving along on a crowned 95 roadway, if the gage wheel of the central member D' rides higher than the members D and D², it will raise the delivery ends of both of the central chutes above the side chutes a distance corresponding to the elevation 100 of the central gage member, and hence the layer of stone will be practically of the same depth at all points. Also, if one of the side members should be raised by the 105 roadway, it will also raise two of the delivery ends of the chutes and effect a practically even distribution of the stone.

The number of gage members as well as the number of chutes may be multiplied as desired, and a separate gage member may be 110 provided for each chute so that the delivery ends of the several chutes will all operate independently. For practical work, however, the arrangement shown in the drawing is satisfactory. If it is desired to place upon 115 a roadway a layer of stone of less width than the entire width of the several chutes, one or more of the gates 18 may be closed before the main gate 17 is opened, and the stone 120 will be laid only on the area traversed by 125 130

the ends of the open chutes. Thus, by proper handling of the gates a roadway, whose width is not an even multiple of the total width of the series of chutes may be 5 covered evenly.

It is important to be able to deliver the stone at the sides of the vehicle—that is, to the right or left of the plane of the vehicle wheels, so that in laying courses of stone 10 side by side, the wheels of the vehicle and the trailing gage members will not travel upon the stone already laid, which would affect the height of the delivery ends of the chutes relatively to the ground. Hence, the 15 casing C, inclosing the several chutes, is wider than the vehicle and extends laterally beyond the planes of the vehicle wheels, and the partitions 3 and 5 diverge downwardly so as to conduct the material from the wagon 20 body, through the side chutes 6 and 9 thereby formed, laterally outward. The subdivision of the main chute or casing C by the partitions into a plurality of smaller chutes effects an important result in the distribution 25 of the stone. In dumping the wagon, if these chutes were omitted, it would be found that because of the lateral enlargement of the casing beyond the width of the wagon body, the material would feed out faster 30 from the rear corners of the wagon body than it would from the middle. As a result, the material would assume a heaped-up or conical form from which the coarser particles would constantly roll down into the 35 corners, thus causing an undesirable segregation of the larger pieces of stone at the sides of the layer delivered upon the roadway. With the larger and smaller pieces of stone evenly mixed when loaded into the 40 vehicle, it is desirable to deliver the stone upon the roadway in the same mixed condition, both between and beyond the planes of the wheels, and by dividing the casing C into a plurality of chutes by partitions extending 45 well up to the floor of the wagon body, it is found that the evenness of the mixture is maintained, the larger pieces from the center no longer tending to roll out into the side portions.

50 While, in the drawing, I have shown the invention applied to an ordinary road wagon, without springs, the invention is particularly applicable to motor driven vehicles in which there are usually springs between the body and the frame. In such motor operated vehicles, loads of different weights and also the change in weight of load, as the latter is lessened during the 55 spreading operation, as well as unevenness 60 of the roadway, will cause the body of the vehicle to vary in height with respect to the roadway, and if the load were delivered onto the roadway from a fixed chute, the depth of the layer of stone would vary 65 because of the movement of the body rela-

tive to the roadway. In my invention, such changes in the height of the body would not materially affect the even distribution of the stone or other material, as, if the rear end of the body should rise, the rollers 30 would move forward on the rails of the gage members, and if the rear end of the body should be depressed, the rollers would adjust themselves rearwardly. Thus, while the inclination of the vertically swinging delivery 70 ends of the chutes would vary with changes in height of the body relatively to the road, this change in inclination would cause a slight swinging of the scraper bars about the axes of the rollers, but would not materially vary the height of the lower edges 75 of the scrapers, if the telescopic ends of the chutes were shortened, because the scrapers would then be suspended close to and directly beneath the axes of the supporting rollers. The extension of the 80 scrapers would cause the scrapers to ride behind the rollers, and the vertical movements of the wagon body would cause the scrapers to swing further, but not to such a degree as 85 to vary the height of the scraper undesirably. The telescopic arrangement of the delivery ends of the chutes permits adjustment for wagon bodies of different heights, as 90 well as for laying the stone in layers of 95 different depths.

While in the drawing the gage members are attached to the vehicle, and this is the preferred arrangement, I may connect the gage members to the chutes. Thus, in some 100 instances, the gage members may be secured directly to the delivery ends of the chutes so as to support the latter and to engage the ground immediately in front of the outlets of the chutes.

What I claim is:

1. The combination with a dumping vehicle of a chute extending from the vehicle and having a vertically movable delivery end, and a trailing gage member connected to the vehicle and adapted to support the delivery end of the chute, said delivery end being movable with respect to the gage member.

2. The combination with a dumping vehicle of a chute connected thereto, said chute having a vertically movable delivery end, and a trailing gage member connected to the vehicle, said member having a ground engaging portion and a part at the rear 110 thereof adapted to support the delivery end of the chute, out of engagement with the ground, said delivery end being movable with respect to the gage member.

3. The combination with a dumping vehicle and a trailing gage member connected to the vehicle, said gage member having a ground engaging portion and a part projecting at the rear thereof, of a chute connected to the vehicle, said chute having a 125 130

vertically movable delivery end adapted to be supported by said rearward extension of the gage member out of engagement with the ground, and a scraper upon the delivery end of the chute, said delivery end being movable with respect to the gage member.

4. The combination with a dumping vehicle and a trailing gage-member connected to the vehicle, of a chute extending from the vehicle and having a hinged delivery end adapted to rest upon said member and movable with respect thereto.

5. The combination with an endwise dumping vehicle and a trailing gage member connected to the vehicle, said gage member having a ground engaging portion and a part projecting at the rear thereof, of a chute extending from the rear of the vehicle and having a vertically movable delivery end, a scraper on said delivery end, and means, substantially in the vertical plane of said scraper, for supporting the delivery end of the chute on the rearwardly projecting part of the gage member.

6. The combination with an endwise dumping vehicle and a trailing gage member connected to the vehicle, said gage member having a ground engaging portion and a rail projecting at the rear thereof, of a chute extending from the rear of the vehicle and having a vertically movable delivery end, a scraper on said delivery end, and means, substantially in the vertical plane of said scraper, for supporting the delivery end of the chute on said rail.

7. The combination with an endwise dumping vehicle and a chute extending from the rear thereof and having a vertically movable delivery end and a scraper on said delivery end, of a trailing gage member comprising a bar hinged to the vehicle and a wheel for engaging the ground, a portion of the bar being adapted to extend rearwardly from the wheel when the latter engages the ground, and the delivery end of the chute having a part adjacent the scraper adapted to rest upon said rearward extension.

8. The combination with an endwise dumping vehicle of a plurality of chutes extending rearwardly therefrom, said chutes having vertically movable delivery ends, a plurality of gage members connected to the vehicle and adapted to engage the ground in front of said delivery ends, said delivery ends adapted to rest upon the gage members.

9. The combination with an endwise dumping vehicle of a plurality of chutes extending rearwardly therefrom, said chutes having vertically movable ends, and scrapers upon said ends, a plurality of gage members connected to the vehicle and adapted to engage the ground in front of said delivery ends, said delivery ends having parts

adjacent the scrapers adapted to rest upon the gage members.

10. The combination with an endwise dumping vehicle of a plurality of chutes having parts fixed to the vehicle body and delivery ends hinged to said fixed portions, of trailing gage members connected to the vehicle and adapted to engage the ground in front of and adjacent to said delivery ends, said gage members adapted to support said delivery ends.

11. The combination with an endwise dumping vehicle of a plurality of chutes having parts fixed to the vehicle body and delivery ends hinged to said fixed portions, and scrapers upon said ends, of trailing gage members connected to the vehicle and adapted to engage the ground in front of said delivery ends, said gage members adapted to support said delivery ends adjacent the scrapers.

12. The combination with an endwise dumping vehicle of a plurality of chutes extending rearwardly therefrom, the side chutes diverging laterally beyond the planes of the vehicle wheels, each chute having a vertically movable delivery end, and gage members connected to the vehicle and adapted to engage the ground, said members adapted to support the delivery ends of the chutes.

13. The combination with an endwise dumping vehicle of a plurality of chutes extending rearwardly therefrom, the side chutes diverging laterally beyond the planes of the vehicle wheels, each chute having a vertically movable delivery end and a scraper thereon, and gage members connected to the vehicle and adapted to engage the ground, said members adapted to support the delivery ends of the chutes at points adjacent the scrapers.

14. The combination with an endwise dumping vehicle of a plurality of chutes extending rearwardly therefrom, the side chutes diverging laterally beyond the planes of the vehicle wheels, each chute having a hinged delivery end, each delivery end comprising a pair of telescopic sections, and a scraper attached to one section of each pair, and gage members connected to the vehicle and adapted to engage the ground in advance of said delivery ends, said members adapted to support the delivery ends of the chutes at points adjacent the scrapers.

15. The combination with an endwise dumping vehicle of a plurality of chutes extending rearwardly therefrom, the receiving ends of said chutes being fixed to the vehicle and the delivery ends being hinged to the fixed portions, a main door or gate for closing the entrances to all of said chutes, and separate gates for closing the individual chutes, and gage members connected to the vehicle and adapted to engage

the ground, said members adapted to support the delivery ends of the chutes.

16. The combination with an endwise dumping vehicle of a chute casing secured to the body and divided by partitions into a plurality of chutes, the side chutes diverging laterally beyond the sides of the body, and vertically movable delivery ends connected to said chutes, of gage members attached to the vehicle and adapted to engage the ground in advance of the delivery ends, said gage members adapted to support said ends.

17. The combination with a dumping vehicle and a plurality of chutes extending therefrom, each chute having a vertically movable delivery end, of gage members attached to the vehicle and extending between the delivery ends, said members adapted to engage the ground, and to support said ends.

18. The combination with a dumping vehicle and a plurality of chutes extending therefrom, each chute having a vertically movable delivery end, of gage members attached to the vehicle and extending between the delivery ends, said members adapted to engage the ground, and each gage member serving as a support for two adjacent delivery ends of the chutes.

19. The combination with a dumping vehicle and a plurality of chutes extending therefrom, each chute having a vertically movable delivery end and a scraper at the rear of its outlet, said scrapers meeting one another end to end, of gage members attached to the vehicle and extending between and adapted to support said delivery ends, said members adapted to engage the ground in advance of the scrapers.

20. The combination with a dumping vehicle and a plurality of chutes extending therefrom, the delivery portions of said chutes being independently movable vertically, of a gage member for supporting the ends of adjacent chutes comprising a yoke hinged to the vehicle, a wheel mounted in the yoke and adapted to engage the ground, and rails or bars extending rearwardly from the wheel between adjacent chute ends and adapted to support the same.

21. The combination with a dumping vehicle and a trailing gage member connected thereto, of a chute having a vertically movable end portion provided with a part rest-

ing on said gage member, and a spring for pressing said part against the gage member.

22. The combination with a dumping vehicle of a chute casing at the rear thereof divided by partitions into a plurality of chutes, said casing having its rear side cut away to form an opening, a swinging door or gate within the casing adapted, in one position, to close the entrances to said chutes and in another position to open the chutes and close the opening in the rear of the casing, an operating shaft, toggle connections between said door and shaft adapted to extend through the opening in the casing, and a plurality of gates for closing the entrances to the individual chutes, said latter gates being accessible through said opening in the casing, the ends of said chutes being adjustable vertically, and gage members for supporting said ends.

23. The combination with an endwise dumping vehicle of a plurality of chutes extending rearwardly therefrom, the receiving ends of said chutes being fixed to the vehicle and the delivery ends being hinged to the fixed portions, a main door or gate for closing the entrances to all of said chutes, and gage members connected to the vehicle and adapted to engage the ground, said members adapted to support the delivery ends of the chutes.

24. The combination with a dumping vehicle of a chute secured to the vehicle and having a delivery end connected directly thereto and vertically movable with respect to the body of the chute, and a trailing gage member adapted to engage the ground and support said delivery end out of engagement with the ground.

25. The combination with a dumping vehicle of a chute secured to the vehicle and having a vertically movable delivery end connected thereto, a trailing gage member adapted to engage the ground and support said delivery end at a fixed distance from the ground, and a scraper secured to said delivery end and adapted to project below the same.

In testimony whereof I have affixed my signature, in presence of two witnesses.

J. GROVE BROWN.
